UNITED STATES PATENT OFFICE.

GEORGE ALBERT WIELAND, OF DULUTH, MINNESOTA.

SUSPENSORY.

SPECIFICATION forming part of Letters Patent No. 688,371, dated December 10, 1901.

Application filed March 19, 1901. Serial No. 51,923. (No model.)

To all whom it may concern:

Be it known that I, GEORGE ALBERT WIELAND, a citizen of the United States, residing at Duluth, in the county of St. Louis and State 5 of Minnesota, have invented certain new and useful Improvements in Suspensories; and I do hereby declare the following to be a full, clear, and exact description of the invention, such as will enable others skilled in the art to 10 to which it appertains to make and use the same.

My invention relates to improvements in anatomical suspensories, and particularly to that class of suspensories designed for the support of the scrotum and contents, and has 15 for its object the provision of a pouch having a regularly-formed aperture or apertures of the required size and shape, the walls thereof being spaced a considerable distance apart at all times, and said aperture or apertures being to one side of the vertical longitudinal mid-sectional line of said pouch and constantly maintained in an open condition to accommodate the male member without inconvenience to the wearer, the aperture in some 20 pouches being on the left-hand side and in others on the right-hand side, so that the purchaser can call for and secure either style, or in some instances the pouch may be constructed with two front apertures, one to one 25 side of the vertical longitudinal mid-sectional line of the pouch and the other on the other side thereof, so that either aperture may be selected, according as the person "dresses" on the right or left hand side.

To this end the invention consists of a pouch 30 constructed of any suitable material having a frontal aperture to one side of the vertical longitudinal mid-sectional line of said pouch, said aperture being at all times the same size 35 and shape and open to receive the male organ without the walls of the aperture having to be spread or the wearer inconvenienced by the walls of the aperture fitting too tightly upon said male organ.

It also consists of a pouch having two frontal 40 apertures, one of which is located to one side of the vertical longitudinal mid-sectional line of the pouch and adjacent to the supporting-band of the pouch and the other aperture being located on the other side of said line, the 45 edges of said apertures being finished around

with binding, and said apertures remaining at all times open and spread apart and of a shape and size to readily receive and accommodate the male member without cutting or 55 rubbing the wearer, one of the apertures being designed to have the male organ project through the same at all times.

In the accompanying drawings, Figure 1 is a perspective view of an improved anatomical 60 suspensory constructed in accordance with my invention. Fig. 2 is a front elevation of a pouch, showing a slightly-modified form of the same.

In suspensories as heretofore constructed, 65 in which the penis is designed to constantly project through an aperture provided in the pouch thereof, said aperture has been located centrally of the vertical longitudinal mid-sectional line of the pouch. I have found from 70 experience and also from the testimony of others that the location of the frontal aperture at this point is often very inconvenient to the wearer, and the inconvenience is most perceptible after having used a suspensory 75 constructed in accordance with my invention. All men either dress on the left or right hand side, and it is for the accommodation of such dressing that my invention is designed, and at the same time to render the suspensory as 80 comfortable as possible to the wearer. The pouch of my suspensory is not intended to contain the penis, but the latter always projects through one of the frontal apertures. The aperture is made of a size and shape to 85 admit of the ready passage of the penis through the same and for its accommodation without crowding or pinching while in this position.

In carrying out my invention A in the 90 drawings represents a pouch constructed of any suitable fabric or webbing, upon the front of which (see Fig. 1) and to one side of the vertical longitudinal mid-sectional line thereof is provided an aperture B. This aperture 95 is of a size and shape usually provided in pouches for the passage of the male member and through which the male member is designed to constantly project. The edges of the opening B are bound around by a finishing-binding b, which not only holds the aperture in shape, but also protects the edges 100

thereof. The aperture is also located at such a point vertically and horizontally from the vertical longitudinal mid-sectional line of the pouch and from the upper edge of the pouch 5 as to best accommodate the male organ and the convenience of the wearer. This location, as seen in the drawings, is preferably at the extreme upper edge of the pouch and near the rear edge thereof.

10 In Fig. 1 I have shown aperture B on the left-hand side of the pouch, which would accommodate a person who dresses on the left-hand side. For a person who dresses on the 15 right-hand side the aperture would be on the right side of the pouch. The pouch is supported by any suitable belt, as C, as shown, and straps D.

By means of my invention the bunching of all the contained parts immediately in front 20 is avoided, and the parts are suspended in a more natural and comfortable position to the trousers of the wearer.

In Fig. 2 I have shown a pouch A' provided with a plurality of finished openings a', 25 one located to one side of the vertical longitudinal mid-sectional line of the pouch and the other located at the other side thereof, the edges of each of the openings being bound around with finishing-binding a². By means 30 of this construction a purchaser can use either frontal aperture desired, and will therefore be enabled to wear the suspensory with convenience and ease, as the parts are permitted to remain in a natural position.

35 Having thus described my invention, what I claim as new, and desire to secure by Letters Patent, is--

1. As an improved article of manufacture, a suspensory provided with a pouch having 40 a frontal aperture located to one side of the vertical mid-sectional line thereof, the walls of said aperture being at all times spaced a considerable distance apart and the aperture being constantly of a shape and size to receive the male member and to accommodate 45

the same continuously without inconvenience to the wearer, substantially as described.

2. As an improved article of manufacture, a suspensory provided with a pouch having 50 a frontal aperture located to one side of the vertical mid-sectional line thereof, the walls of said aperture being bound around with a suitable finishing-binding and at all times spaced a considerable distance apart and the aperture being constantly of a shape and size 55 to receive the male member and to accommodate the same without inconvenience to the wearer, substantially as described.

3. As an improved article of manufacture, a suspensory provided with a pouch having 60 a frontal aperture to one side of the vertical mid-sectional line thereof and adjacent to the supporting-band of the pouch, the walls of said aperture being bound around with a suitable finishing-binding and at all times 65 spaced a considerable distance apart, the aperture being constantly of a shape and size to receive the male member and to accommodate the same continuously without inconvenience to the wearer, substantially as described. 70

4. As an improved article of manufacture, a suspensory provided with a pouch having frontal apertures, each of which is located to one side of the vertical mid-sectional line of 75 the pouch, the walls of said apertures being bound around with suitable finishing-binding and being at all times spaced a considerable distance apart, and each of the apertures being constantly of a shape and size to receive the male member and to accommodate the same without inconvenience to the wearer, substantially as described. 80

In testimony whereof I hereunto affix my signature in presence of two witnesses.

GEORGE ALBERT WIELAND.
